(57) **CLAIM**

We claim the ornamental design for an ironing board with steam hanger, as shown and described.

DESCRIPTION

FIG. 1 is a perspective view of an ironing board with steam hanger showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is an enlarged view of a portion of the ironing board with steam hanger of FIG. 1;

FIG. 9 is a perspective view of the ironing board with steam hanger showing an alternate configuration with the steam hanger popped-up;

FIG. 10 is a front elevation view thereof;

FIG. 11 is a rear elevation view thereof;

FIG. 12 is a left-side elevation view thereof;

FIG. 13 is a right-side elevation view thereof;

FIG. 14 is a top plan view thereof;

FIG. 15 is a bottom plan view thereof;

FIG. 16 is an enlarged view of a portion of the ironing board with steam hanger of FIG. 9;

FIG. 17 is a perspective view of the ironing board with steam hanger showing an alternate configuration with the steam hanger unfolded to both sides;

FIG. 18 is a front elevation view thereof;

FIG. 19 is a rear elevation view thereof;

(Continued)

FIG. 20 is a left-side elevation view thereof;
 FIG. 21 is a right-side elevation view thereof;
 FIG. 22 is a top plan view thereof;
 FIG. 23 is a bottom plan view thereof; and,
 FIG. 24 is an enlarged view of a portion of the ironing board with steam hanger of FIG. 17.
 The broken lines shown in the figures depict portions of the ironing board with steam hanger that form no part of the claimed design. The dashed broken line in FIGS. 8, 16 and 24 shows the boundary of the enlarged view and forms no part of the claimed design.
